JACOB DAVIS, OF UNIONTOWN, PENNSYLVANIA.

SPRING-MOTOR MECHANISM.

1,212,787.

Specification of Letters Patent. Patented Jan. 16, 1917.

Application filed March 22, 1916. Serial No. 85,832.

To all whom it may concern:

Be it known that I, FRANK MAGIDSON, a citizen of the United States, and resident of Brownsville, in the county of Fayette and State of Pennsylvania, have invented certain new and useful Improvements in Spring-Motor Mechanism, of which the following is a specification.

This invention relates to a spring motor 10 designed primarily for oscillating a cradle or other swinging body, and one object is to provide an escapement of novel construction for transmitting positive back and forth movements to such body. The escapement mechanism is of a type wherein oppositely arranged levers coact with different portions of a toothed escapement wheel, and one of the objects herein is to provide improved means for connecting the levers located at opposite sides of the shaft which carries the ratchet wheel.

In the accompanying drawings Figure 1 is a longitudinal sectional elevation of the improved motor mechanism, and Fig. 2 is a 25 similar view of the escapement end of the mechanism, taken at right angles to Fig. 1. Fig. 3 is a cross section on line 3—3 of Fig. 1. Fig. 4 is a cross section on line 4—4 of Fig. 1. Fig. 5 is a detail view of the washer-like element interposed between the core sections.

The motor mechanism is preferably arranged within and supported by an elongated casing 13 of rectangular form 35 which may be secured at its opposite ends by cross-bars 8 and 8' of a support of suitable form. This casing is closed at one end by head 14 in which is formed a bearing for the short shaft 15, the squared extremity 15' 40 of the latter being adapted to receive a crank for winding up the motor. Carried by the inner end of this shaft is the peripherally toothed sprocket wheel 17, and projecting inwardly therefrom is the core or 45 spool-like support for the elongated coiled motor spring 18. The spool or core is formed in sections, 20 being the end section secured by lugs 19 and pin 19' to the inner side of ratchet wheel 17. 21 designates the 50 inner end section of the core which is non-rotatably supported by pin 22, the latter disposed diagonally in casing 13 with its extremities confined in the casing angles as shown. Between the end sections 20 and 21 55 are the intermediate sections 23, which are

rotatable on a shaft 24 extending therethrough, and with the opposite ends of said shaft grooved at 24' and rotatably confined in core sections 20 and 21 by screws 25. Thus it will be seen that the only non-rotatable portion of the core is the innermost section 21, the opposite end section 20 and the intermediate sections 23 being rotatable relatively to each other, and as connecting shaft 24 is itself rotatably held, the movable spool sections may rotate either with said shaft or independently thereof. By this means every possible facility is provided for preventing the motor spring 18 when wound up from deflecting laterally 70 and so gripping and binding the core as to interfere with a uniform and regular application of the spring force to the driven mechanism. Thus, even if the lateral deflection of the spring at one point tends to 75 grip one section of the core, the remaining sections are in no wise affected and may turn freely in response to the unwinding action of the spring.

Interposed between the adjacent spool sections are the washer-like plates or heads 26 having their edges notched and with the resulting point-like projections 27 bent or deflected in opposite directions to overhang the adjacent spool sections, thereby bridging the 80 joint between the sections and preventing convolutions of spring 18 from working therebetween which if permitted might result in clogging the mechanism and seriously 85 impairing the operation. Plates 26 are 90 loosely arranged and may turn either with the spool sections, or if impinged by the spring may be held against turning without retarding the operation.

The escapement mechanism which co-95 operates with ratchet wheel 17 is embodied in the two levers 30 and 31 arranged at opposite sides of shaft 15 and extending past opposite portions of the ratchet wheel periphery. These levers are pivoted at their 100 inner ends at 30' and 31', respectively, to a plate 32' secured to the annular boss 32 of casing head 14. The levers are connected for unitary movement by the bodily movable ring-like link 33 encircling shaft 105 15, an arm 34 projecting from lever 30 and pivoted to said link at 34', and a similar arm 35 projecting from the opposite side of lever 31 and pivotally connected at 35' to link 33. Lever 30 extends through a 110

slot in the top of casing 13 and is entered in notch lug 10' of link 10, whereby the vibrations of said lever are imparted to the body to be vibrated.

5 Pivoted to levers 30 and 31, respectively, are the oppositely disposed dogs or pawls 36 and 37 which are adapted to engage the notches of wheel 17 as in Figs. 1 and 3. A spring 38 connects dog 36 with pivot post 30' of lever 30, and a like spring 39 similarly connects dog 37 with post 31' of lever 31. With the parts thus arranged, it will be seen that movement of levers 30 and 31 in either direction from a straight line position will place the springs 38 and 39 under tension which results in pivotally moving dogs 36 and 37 either into or out of engagement with the teeth of ratchet 17, depending on the direction of movement of the levers. Thus, with the levers in the position shown in Fig. 4, the movement of lever 30 toward the left has resulted in so deflecting spring 38 as to cause dog 36 to engage the ratchet as seen in Fig. 3, and at the same time the opposite deflection of spring 39 has resulted in a reverse movement of dog 37, thereby disengaging it from the ratchet wheel. The movements thus described result from the arrangement, characteristic of the present invention, whereby the link-connected levers 30 and 31 move simultaneously in the same direction, first toward one side of the casing and then toward the opposite side.

35 It is further characteristic of the escapement mechanism that the levers 30 and 31 are positively impelled through each vibration thereof, and the result of this is that the swinging body is positively driven through each oscillation, and not simply driven through the oscillations in one direction and with the momentum thereof depended on for the opposite oscillations. This positive movement in each direction results from the coöperation of the pivoted dogs with the ratchet. Thus, as lever 30 moves toward the right from the position shown in Figs. 3 and 4, the unwinding or impelling movement of the portion of ratchet 17 engaged by dog 36 is in the same direction; whereas the corresponding movement of dog 37 with the portion of wheel 17 which it is to engage is in direction opposite to the movement of said wheel portion, so that the wheel and dog 37 are brought into engagement when moving in opposite directions, and thereby dog 37 is positively engaged with the opposite ratchet tooth by the time lever 30 has been shifted sufficiently far to the right to disengage dog 36. Hence, for the next beat or oscillation dog 37 is in positive engagement with and moves with ratchet 17 when the above described operation is repeated excepting that lever 31 is then active in transmitting the

force from ratchet 17 while lever 30 is moving its dog 36 into a new operative position. With levers 30 and 31 connected by the bodily movable ring-like link 33 the levers are properly united and caused to move in unison notwithstanding their arrangement at opposite sides of shaft 15.

The arrangement is such that upon stopping the body being vibrated the dog-carrying levers hold the mechanism still or inoperative until the body is again started to swing, whereupon the escapement will immediately become active and will continue to operate until the body is again stopped or until the motor has been completely unwound.

That portion of the structure relating to the motor spring and the mounting therefor is claimed in my application filed July 15, 1916, Serial No. 109,423.

I claim:

1. A spring motor mechanism comprising a spring-impelled ratchet wheel, two levers extending to different portions of the periphery of the wheel and each having a fixed pivotal mounting, a connecting device to which each lever is pivoted, said device extending around the wheel-axis and adapted to move bodily when the levers are moved, reversely disposed dogs pivoted to the levers and adapted to engage different portions of the ratchet wheel, and a spring for each dog actuated by the movement of the lever carrying such dog for moving the latter alternately into and out of engagement with the ratchet wheel.

2. A spring motor mechanism comprising a spring-impelled ratchet wheel, two levers having fixed pivotal supports at opposite sides of the axial center of the wheel and extending from their supports toward different portions of the wheel periphery, a bodily movable link extending around the wheel axis and with opposite portions thereof connected to the respective levers, reversely disposed dogs pivoted to the levers, springs actuated by the movements of the levers for engaging one dog with the said wheel and simultaneously disengaging the other dog therefrom, and a body mounted to oscillate and operatively connected to one of the levers.

3. A spring motor mechanism comprising a spring-impelled shaft, a ratchet wheel secured to said shaft, a fixed support extending to opposite sides of the shaft, levers pivoted at their inner ends to the support and with their free portions extending toward different portions of the wheel periphery, a bodily movable link extending around said shaft and at opposite sides of the latter pivotally connected to the respective levers whereby the free portions of the levers are caused to move simultaneously in the same direction, reversely disposed dogs pivoted to the respective levers, means actuated by the

movements of the levers for engaging one dog with the ratchet wheel and simultaneously disengaging the other dog therefrom and vice versa, and a body mounted to oscillate and operatively connected to one of the levers.

4. A spring motor mechanism comprising a spring-impelled ratchet wheel, two levers having fixed pivotal mountings at opposite sides of the wheel axis and extending in opposite directions therefrom, a bodily movable link extending around the wheel axis, arms extending in opposite directions from the respective levers with said arms pivotally

connected to opposite portions of said link, 15 reversely disposed dogs pivotally mounted on the respective levers, springs actuated by the movements of the levers for engaging one dog with the ratchet wheel and simultaneously disengaging the other dog there- 20 from and vice versa, and a body mounted to oscillate and operatively connected to one of the levers.

FRANK MAGIDSON.
